UNITED STATES PATENT OFFICE.

JOHN S. HUGHES, OF HUDSON, AND CHARLES J. PRANKARD, OF TROY,
NEW YORK, ASSIGNORS TO JOHN LEGGETT & SON, OF TROY, NEW
YORK, A FIRM.

MACHINE FOR CUTTING AND PASTING PAPER.

No. 838,252.

Specification of Letters Patent.

Patented Dec. 11, 1906.

Application filed December 22, 1897. Serial No. 663,095.

To all whom it may concern:

Be it known that we, JOHN S. HUGHES, residing at Hudson, county of Columbia, and CHARLES J. PRANKARD, residing at Troy, county of Rensselaer, State of New York, citizens of the United States, have invented certain new and useful Improvements in Machines for Cutting and Pasting Paper, of which the following is a specification.

10 The invention relates to such improvements; and it consists of the novel construction and combination of parts hereinafter described and subsequently claimed.

Reference may be had to the accompanying drawings, and the letters of reference marked thereon, which form a part of this specification.

Similar letters refer to similar parts in the several figures therein.

20 Figure 1 of the drawings is a view in side elevation of our improved machine. Fig. 2 is a view in front elevation of the same. Fig. 3 is a horizontal section taken centrally through the cutter-roll and longitudinal cutter on the broken line 3 3 in Fig. 1. Fig. 4 is a vertical section taken centrally through the paste-wheel on the broken line 4 4 in Fig. 1. Fig. 5 is a vertical section taken centrally through the draft - rolls on the 25 broken line 5 5 in Fig. 1. Fig. 6 is a vertical section taken on the broken line 6 6 in Fig. 2 through the transverse knives and the grooved portions of the draft-rolls and bed.

The object of our invention is to provide 35 mechanism for automatically dividing a web of paper into small sheets and delivering the sheets with one or more edges pasted.

A is the frame of our improved machine, from which are erected the standards B, 40 containing bearings for the paper-roll support; the standards C, containing bearings for the cutter-roll C'; the standard C², containing bearings for the longitudinal cutter C³; the standards D, containing bearings for the draft-rolls D', and the standards E, containing slideways for the knife E'.

The roll-holder is of the usual form for supporting a web of paper in a roll from which the paper is withdrawn by rotating the roll.

50 The web of paper from the roll passes around the cutter-roll C', which is provided intermediately of its ends with a peripheral

groove C⁴, into which the paper is forced by the sharp edge of the rotary cutter C³, whereby the web is divided along its longitudinal middle as it is drawn between the cutter and cutter - roll by the rotation of the draft-rolls D'.

Intermediately of the draft-rolls and cutter-roll is located the paste-wheel F, mounted 60 upon the shaft F', rotary in bearings on the walls of the paste-reservoir F².

The paste-reservoir is attached to the machine-frame, and the paste-wheel is supported with the lower portion of its periphery within 65 the reservoir and immersed in the paste contained therein, while its upper portion projects above the reservoir into the path along which the cut edges of the web of paper travel.

70 The cut edges of the paper lie closely together at the middle of the web, and in passing over the paste - wheel as the web is drawn along by the draft-rolls the paper is supplied with a coating of paste along the 75 cut edges. The outer portions of the web are supported during the pasting operation by the drums F³ on either side of the paste-wheel. After the paste has been thus applied to the cut edges along the middle of the 80 web the paper passes under a tension-rod T to the draft-rolls. The tension-rod is vertically adjustable in the frame of the machine, whereby the tension upon the paper may be varied. The draft-rolls are constructed with 85 a middle peripheral groove D², adapted to receive the cut and pasted edges of the web as the paper is drawn along by the engagement therewith of the ungrooved surfaces of the rolls. The grooves D² prevent the pasted 90 portions of the paper from being brought into contact with the surfaces of the rolls to soil the same. As the draft-rolls are rotated the longitudinally cut and pasted web is forced out from between the draft-rolls upon a delivery-table, which may be of any known 95 form.

We have shown in the drawings a preferred form of table especially adapted for the delivery of thin paper and comprising a rectangular frame G, supported upon the frame of the machine at G' and provided with a convexed top formed of a plurality of bowed rods extending longitudinally of the frame.

The frame is adjustable upon its support, whereby the inclination of the frame can be varied.

Intermediately of the delivery-table and draft-rolls is a supporting-bed H for the paper and mechanism for cutting the web of paper transversely, comprising a horizontal knife K, fixed just above the bed H, and a vertically-movable knife E', adapted to co-operate with the fixed knife to cut the paper. The bed H, adjacent to which is the pasted surface of the paper, is provided with a groove H', similar in form and function to the grooves in the draft-rolls. The knife E' is vertically-movable in slideways in the standards E to and from the fixed knife K.

As a means for operating the draft-rolls and knife E' we have shown a power-shaft S, provided with fixed and loose pulleys S' and S'', adapted to receive the driving-belt S³, which shaft is connected with a counter-shaft S⁴ by the belt S⁵ and pulleys S⁶ and S⁷. The shaft S⁴ is provided with a pinion S⁸, which meshes with a gear S⁹ on the crank-shaft P. A crank P' on the inner end of the crank-shaft is connected by the pitman P² with the movable knife E', whereby the rotary movements of the crank-shaft impart to the knife vertically-reciprocating movements in its slideways. The other end of the crank-shaft is provided with a crank-arm P³, upon the wrist-pin P⁴ of which is pivoted the lower end of the rack P⁵. The upper end of the rack is movable in a box or slideway P⁶, pivoted at P⁷, and is provided with teeth adapted to mesh with a pinion P⁸, fixed upon the shaft P⁷. The ratchet-wheel P⁹ is also fixed upon the shaft P⁷ and rotates therewith and with the pinion P⁸. The gear-wheel P¹⁰ is rotary upon the shaft P⁷ and meshes with a pinion D² on the spindle of one of the draft-rolls. The draft-rolls are connected by gears D⁴. A pawl D³ connects the gear P¹⁰ with the ratchet, whereby the gear is operated by the rotary movements of the ratchet in one direction only.

The operation of the driving mechanism is as follows: The crank-shaft having a constant rotary movement imparts to the knife E', as well as to the rack P⁵, vertically-reciprocating movements, by means of which the knife is brought into and out of co-operation with the fixed knife and the rack is caused to slide up and down in its slideway-box, thereby rotating the pinion P⁸ and ratchet first in one direction and then in the opposite direction. The rotary movement imparted to the pinion and ratchet by the upward movement of the rack is in a direction to cause the gear P¹⁰ to be rotated by means of the pawl D³ and to thereby operate the draft-rolls to feed the paper out upon the delivery-table. The movement imparted to the pinion and ratchet by a downward movement of the rack is in a direction to cause the pawl to slip over the

ratchet-teeth without operating the gear P¹⁰. The cranks are so fixed on the crank-shaft that the idle period of the gear P¹⁰ and the draft-rolls is simultaneous with the period of co-operation of the knives. The length of the sheet of paper delivered to the table between each two successive operations of the knives is determined by the throw of the crank P'. As a means for varying the throw of said crank to adapt the machine for the delivery of larger or smaller sheets we attach the wrist-pin P⁴ to a slide-nut N, movable in a longitudinal slideway in the crank-arm and adapted to be operated by a screw N', passing through the nut. By rotating the screw the nut and wrist-pin can be moved along the slideway toward or from the center of the crank-shaft, thereby changing the effective length of the crank-arm.

The longitudinal and transverse cutters may be of any known form.

What we claim as new, and desire to secure by Letters Patent, is—

1. In a machine for cutting and pasting paper, the combination with a cutter adapted to divide a web of paper longitudinally; and a cutter adapted to divide the web transversely; of pasting mechanism located in the path of the web intermediately of said longitudinal and transverse cutters. 95

2. In a machine for cutting and pasting paper, the combination with a cutter adapted to divide a web of paper longitudinally; of a cutter adapted to divide the web transversely; and pasting mechanism located intermediately of said longitudinal and transverse cutting mechanism, and in line with the longitudinal cut edges of the web and a pair of draft-rolls having a peripheral groove in the path of the pasted portions of the web. 105

3. In a machine for cutting and pasting paper, and in combination, a roll-support for a web of paper; a cutter-roll and co-operating longitudinal cutter; a rotary paste-wheel in the path of the cut edges of the web; a pair of draft-rolls having a peripheral groove in the path of the cut and pasted edges of the web; and a transverse cutter, substantially as described. 110

4. In a machine for cutting and pasting paper, and in combination, a longitudinal cutter located in the path of a web of paper; a paste-wheel located in the path of the cut edges of the web; web-supporting drums on either side of the paste-wheel; a pair of draft-rolls grooved to receive the cut and pasted edges of the web; and a transverse cutter, substantially as described. 115

5. In a machine for cutting and pasting paper, and in combination, pasting mechanism located in the path of a web of paper; a fixed horizontal knife; a vertically-movable knife; a supporting-bed for the paper below the horizontal knife; and a pair of draft-rolls between the pasting mechanism and knives; 125

130

the rolls and bed being provided with grooves in the path of the pasted portion of the web, substantially as described.

6. In a machine for cutting and pasting paper, and in combination, a continuously-acting cutter adapted to divide the web longitudinally; a paste-wheel in the path of the cut edges of the web; a pair of draft-rolls; a transverse cutter; a power-shaft; connections between the power-shaft and transverse cutter; and an intermittent gear connection between the power-shaft and draft-rolls, substantially as described.

7. In a machine for cutting and pasting paper, the combination with a cutter adapt-

ed to divide a web of paper longitudinally; and a cutter adapted to divide the web transversely; of pasting mechanism located in the path of the web intermediately of said longitudinal and transverse cutters, and a pair of ²⁰ draft-rolls having a peripheral groove in the path of the pasted portions of the web.

In testimony whereof we have hereunto set our hands this 9th day of December, 1897.

JOHN S. HUGHES.
C. J. PRANKARD.
